(57) **CLAIM**

The ornamental design for an electric wheelchair, as shown and described.

DESCRIPTION

1. Electric wheelchair

1.1 : Bottom

1.2 : Front

1.3 : Left

1.4 : Back

1.5 : Right

1.6 : Top

1.7 : Perspective

A powered wheelchair driven through all 4 wheels, large wheels to the front, omni-wheels to the rear; controls and feedback provided to the operator through armrest mounted devices; the device supports a lifting arm to adjust the height of the seated occupant.
